POP-OUT HANDLE AND LOCK UNIT

Robert K. Unter, Rockford, Ill., assignor to Keystone Consolidated Industries Inc., a corporation of Delaware

Filed Mar. 21, 1968, Ser. No. 11,082

Term of patent 14 years

Int. Cl. D8—03

U.S. Cl. D8—120

FIG. 1.

FIG. 2.

FIG. 3.

FIG. 4.

FIG. 5.

FIG. 6.

FIG. 7.

FIGURE 1 is a perspective view of a pop-out handle and lock unit in closed position, embodying my new design;

FIG. 2 is a side elevational view thereof;

FIG. 3 is a front elevational view thereof;

FIG. 4 is a top plan view thereof;

FIG. 5 is a perspective view thereof with the handle shown in its extended position;

FIG. 6 is a side elevational view thereof with the handle extended; and

FIG. 7 is a top plan view thereof with the handle extended.

I claim:

The ornamental design for a pop-out handle and lock unit, substantially as shown.
